UNITED STATES PATENT OFFICE.

EUGENE F. McDONALD, JR., OF CHICAGO, ILLINOIS.

DESIGN FOR A RADIO CABINET.

Application filed December 21, 1922. Serial No. 4,652. Term of patent 3½ years.

To all whom it may concern:

Be it known that I, EUGENE F. McDONALD, Jr., a citizen of the United States, residing at Chicago, in the county of Cook and State of Illinois, have invented a new, original, and ornamental Design for Radio Cabinets, of which the following is a specification, reference being had to the accompanying drawing, forming a part thereof.

I claim:

The ornamental design for a radio cabinet, as shown.

EUGENE F. McDONALD, JR.
